CLAIM

The ornamental design for a beverage container, as shown and described.

DESCRIPTION

FIG. 1 is a front, top perspective view of a beverage container showing my new design;

FIG. 2 is a front view thereof;

FIG. 3 is a side elevation view thereof;

FIG. 4 is a top plan view thereof; and,

FIG. 5 is a front, top perspective view of a beverage container with the interior circle shown in broken lines for clarity of illustration.

The broken line showing of the bottle is included for the purpose of illustrating only and forms no part of the claimed design.
